DESIGN FOR A FLASHLIGHT

Colin Douglas Barrett, Watertown, Conn., assignor to Scovill Manufacturing Company, Waterbury, Conn., a corporation of Connecticut

Application October 2, 1936, Serial No. 65,147

Term of patent 14 years

To all whom it may concern:

Be it known that I, Colin D. Barrett, a citizen of the United States of America, residing at Watertown, in the county of Litchfield and State of Connecticut, have invented a new, original, and ornamental Design for Flashlights, of which the following is a specification, reference being had to the accompanying drawing, forming a part thereof.

Fig. 1 is a front elevation of the flashlight, showing my new design.

Fig. 2 is a side elevation of the same.

Fig. 3 is a front end view of the same.

Fig. 4 is a rear end view of the same.

I claim:

The ornamental design for a flashlight, as shown.

COLIN DOUGLAS BARRETT.
